UNITED STATES PATENT OFFICE.

WILLIAM PASCHALL, OF BIRMINGHAM, ALABAMA.

STRAIGHT-EDGE.

1,201,617.

Specification of Letters Patent. Patented Oct. 17, 1916.

Application filed December 18, 1915. Serial No. 67,574.

To all whom it may concern:

Be it known that I, WILLIAM PASCHALL, a citizen of the United States, residing at Birmingham, in the county of Jefferson and State of Alabama, have invented a new and useful Straight-Edge, of which the following is a specification.

The device forming the subject matter of this application is a straight edge resembling in some particulars, the straight edge shown in my prior Patent No. 713,141, granted on the 11th day of November, 1902.

The straight edge herein disclosed preferably is made up of opposed plates which are cemented together. A binding strip extends along the edges of the plates and is provided with a fin which enters between the plates.

One object of the invention is to provide, upon this fin, projecting prongs, adapted to engage one or both of the plates.

Another object of the invention is to provide novel means whereby the plates will be held against separation in one direction, and whereby the binder strips will be prevented from separating in a rectangularly disposed direction, this result being brought about by inserting a channel member into the ends of the plates and by riveting down the ends of the channel member on the aforesaid strips.

A further specific improvement resides in the fact that between the constituent plates of the straight edge there is disposed, a zig-zag truss member which may or may not be secured to the fins which project inwardly between the plates from the binding strips.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

In the accompanying drawing: Figure 1 shows the invention in top plan, a portion of one of the constituent plates of the straight edge being broken away; Fig. 2 is an elevation of the straight edge forming the

subject matter of this application; Fig. 3 is a cross section on the line 3-3 of Fig. 1; Fig. 4 is a fragmental longitudinal section of the complete straight edge; Fig. 5 is a cross section of the binding strip; Fig. 6 is a fragmental longitudinal section on the line 6-6 of Fig. 1; Fig. 7 is a composite perspective view of one of the binding strips and the channel-shaped tie which coacts therewith; Fig. 8 is an end elevation, diagrammatic in nature and illustrating the means whereby the channel-shaped tie member is interlocked with the binding strips to prevent a lateral separation thereof; Fig. 9 is a cross section showing a slight modification in the binding strip delineated in Fig. 5; Fig. 10 is an elevation of a modified form of straight edge, one of the constituent plates of the straight edge being removed, the modification consisting in arranging the zig-zag truss member in a slightly different manner from that shown in Fig. 1.

The straight edge forming the subject matter of this application embodies a pair of plates 1 of any desired length and ordinarily fashioned from wood. A pair of T-shaped binders are provided, each binder embodying a strip 2 which engages the longitudinal edges of the plates 1. The strip 2 is provided intermediate its longitudinal edges and upon its inner face with a dovetailed recess 3 adapted to receive an enlarged, correspondingly shaped bead 4 having a fin 5 which constitutes a part of each binding strip, the fins 5 entering between the plates 1. The fins 5 may be equipped with anchoring openings 6 of any desired contour. Prongs 7 are struck from the fins 5, the prongs preferably, but not necessarily, extending in opposite directions from each of the fins 5, so as to engage both of the plates 1.

In the ends of the edge strips 2 notches 8 are formed, these notches defining tongues 100 11. The invention comprises a channel-shaped tie 9, so-called because it serves to prevent the plates 1 from separating in one direction, and serves also to prevent the edge strips 2 from separating in a rectangularly disposed direction. In the ends of the plates 1, grooves 14 are formed, the flanges of the tie 9 being received in these grooves. The crown of the tie 9 is cut away as shown at 10 to define extensions 12 received in the notches 8 of the edge strips 2. After the extensions 12 have been mounted in the notches

8 as above indicated, the extremities of the extensions are butt-ended and smoothed off as shown at 15.

From the foregoing it will be obvious that 5 the tie 9 exercises an important function, since it locks together the constituent plates 1 of the straight edge, and locks together also, the strips 2 which extend along the opposed longitudinal edges of the straight 10 edge. Since the crown of the tie 9 is cut away as shown at 10, the end face of the tongue 11 is adapted to lie flush with the outer face of the crown of the tie 9. Consequently, the outer face of the strip 2 and 15 the end face thereof are made efficient for defining clearly and sharply, one corner of the straight edge.

Interposed between the plates 1 and extended longitudinally of the straight edge 20 is a zig-zag truss 16 formed by folding a strip of metal upon itself, as shown at 17. This folding operation, however, may be dispensed with and the truss may be otherwise constructed, provided that its zig-zag 25 form is retained. In one form of the invention, as shown in Fig. 1, the angles of the zig-zag truss 16 overlap the inner edges of the fins 5. The parts above described may be secured together in any desired manner.

30 One efficient means for producing this result is by fashioned interfitting projections 18 on the fins 5 and on the angles of the truss 16. In this connection it is to be understood that Fig. 6 is to a large extent 35 diagrammatic in nature, the truss 16 and the edge binders being fashioned from relatively thin metal and that the structure, when viewed in cross section, will not present the bulky appearance indicated in 40 Fig. 6.

If desired, the truss need not be secured to the fins 5, such a construction being shown in Fig. 10, wherein the truss is indicated by the reference character 19. When 45 it is desired to manufacture the straight edge at a minimum expense, the truss may be omitted. Further, when it is desired to cheapen the cost of construction, the edge strip 20 may be formed integrally 50 with the fin 21, as shown in Fig. 8.

The plates 1 are connected by cement, indicated at 22, this cement entering the anchoring openings 6 in the fins 5. Further, it is obvious that the constituent members of the truss 16 or 19 are also embedded 55 in the cement 22, an unusually strong structure thus being afforded. It is to be observed that the anchoring openings 6 lie en-

tirely within the flanges 5. There are, therefore, no gaps along the inner edge of the fin 5 and the anchorage is made more complete and secure. The structure shown in this application has been applied to the straight edge, but it may be used for binding and reinforcing spirit levels and other tools 65 of a like sort.

Having thus described the invention, what is claimed is:—

1. A straight edge comprising a pair of plates having grooves at their ends; a binder 70 embodying a strip engaging the longitudinal edges of the plates and an angularly disposed fin entering between the plates, the strip having notches in its ends; and a channel-shaped tie seated in the grooves 75 and in the notches.

2. A straight edge comprising a pair of plates having grooves in their ends; a binder embodying a strip engaging the longitudinal edges of the plates and an angularly disposed fin entering between the plates, the strip having notches in its ends and defining 80 a tongue; and a channel-shaped tie seated in the grooves and in the notches, the crown of the tie being cut away to receive the 85 tongue, whereby the end face of the strip and the outer side face thereof may define one of the corners of the straight edge.

3. A straight edge comprising a pair of plates; a binder embodying a strip engaging 90 the longitudinal edges of the plates and an angularly disposed fin entering between the plates; and a zig-zag truss member disposed between the plates and extended longitudinally of the plates, the angles of the 95 truss member coacting with the fins.

4. A straight edge embodying a pair of plates; a binder including a strip engaging the longitudinal edges of the plates and an angularly disposed fin entering between the 100 plates, the fin being provided with prongs engaging one of the plates.

5. A straight edge embodying a pair of plates; a binder including a strip engaging the longitudinal edges of the plates and an 105 angularly disposed fin entering between the plates, the fin being provided with oppositely projecting prongs engaging the respective plates.

In testimony that I claim the foregoing 110 as my own, I have hereto affixed my signature in the presence of two witnesses.

WILLIAM PASCHALL.
